(57) **CLAIM**

The ornamental design for the fibrotic band interrupter and implant introducing device, as shown and described.

DESCRIPTION

FIG. 1 is a first perspective view of the fibrotic band interrupter and implant introducing device, showing the plunger in the advanced position;

FIG. 2 is a second perspective view of the fibrotic band interrupter and implant introducing device, showing the plunger in the retracted position;

FIG. 3 is a first side view of the fibrotic band interrupter and implant introducing device, showing the plunger in the advanced position;

FIG. 4 is a second side view of the fibrotic band interrupter and implant introducing device, showing the plunger in the retracted position;

FIG. 5 is a first end view of the fibrotic band interrupter and implant introducing device; and,

FIG. 6 is a second end view of the fibrotic band interrupter and implant introducing device.
